UNITED STATES PATENT OFFICE.

LESTER R. WELLMAN, OF CHICAGO, ILLINOIS, ASSIGNOR TO FRIEDELEY VOSHARDT CO.,
OF CHICAGO, ILLINOIS, A CORPORATION OF ILLINOIS.

DESIGN FOR A CHANDELIER-BODY.

48,847.

Specification for Design.

Patented Apr. 11, 1916.

Application filed January 27, 1916. Serial No. 74,709. Term of patent 7 years.

To all whom it may concern:

Be it known that I, LESTER R. WELLMAN, a citizen of the United States, residing at Chicago, in the county of Cook and State of Illinois, have invented a new, original, and ornamental Design for a Chandelier-Body, of which the following is a specification, reference being had to the accompanying drawing, forming part thereof.

Figure 1 is a side elevation of a chandelier body, showing my new design. Fig. 2 is a bottom view of the same.

I claim:

The ornamental design for a chandelier body, as shown.

LESTER R. WELLMAN.
